RECOVERY OF SULFUR COMPOUNDS
FROM PETROLEUMRobert E. Barieau, Berkeley, Calif., assignor to
California Research Corporation, San Fran-
cisco, Calif., a corporation of Delaware

Application July 13, 1948, Serial No. 38,397

8 Claims. (Cl. 196—31)

1

This invention relates to a method of extracting sulfur compounds from crude petroleum oils or from distillation fractions of these crude oils. More particularly, this invention relates to a method of separating sulfur compounds from petroleum crude oils or fractions thereof having a medium to high sulfur content by a two-stage acid extraction process.

An object of this invention is to recover a concentrate consisting predominantly of organic sulfur compounds from crude petroleum oils or fractions of crude petroleum oils.

A further object is to effect a substantial degree of desulfurization of crude petroleum or fractions of crude petroleum by concentrating the sulfur compounds contained therein in an extract by means of a two-stage acid extraction process.

A variety of sulfur compounds have been identified in petroleum oils and crude concentrates of these compounds are known to be useful in the preparation of weed-killing compositions and surface-active agents. Such concentrates may be further processed to separate sulfur compounds individually or according to chemical type.

It has been discovered that an extract consisting predominantly of organic sulfur compounds can be obtained from crude petroleum oils or petroleum fractions by a method comprising a two-stage acid extraction wherein the concentration of the acid used in the first extraction step is lower than that of the acid used in the second extraction step.

It has also been discovered that the acid of lower concentration used in the first extraction step removes from petroleum stocks of medium to high sulfur content, components of these stocks which are of a non-sulfurous nature. The extract containing the non-sulfurous components is small in volume and has a relatively low overall sulfur content. Thus, the acid of lower concentration effects a selective removal of the non-sulfurous components, which would be removed together with and as an impurity in such sulfur

2

compounds that might be extracted in a single extraction employing a more concentrated acid.

Extraction of the raffinate of the first extraction step with an acid of higher concentration has been found to produce an extract containing a higher percentage of sulfur compounds than it is possible to obtain in a single extraction.

Further, it has been discovered that there exist preferred acids and acid concentration ranges for both extraction steps.

The mineral acids are particularly suitable for use in the first extraction step; especially strong mineral acids such as hydrofluoric, perchloric, and sulfuric acids. From data gathered in the extraction of Santa Maria gas oils with these acids, concentrations of between about 50 to about 80 per cent in the first extraction step can be used with the preferred concentrations being:

	Per cent
Hydrofluoric acid	80
Sulfuric acid	80
Perchloric acid	70

Hydrofluoric acid is employed in the second extraction step at a concentration of at least 85 per cent and preferably at a concentration of about 85-86%.

The first extraction step in the process of the invention produces an extract consisting principally of readily extractable non-sulfur compounds, while the second step produces an extract consisting predominantly of sulfur compounds.

The three acids which may be employed in the first extraction step are approximately equivalent in their extractive action; however, the preferred concentrations differ for the acids as shown above.

Generally it is preferred to conduct both extraction steps under normal conditions of temperature and under sufficient pressure to maintain the materials in liquid phase. However, it is possible to conduct the extractions at reduced or elevated temperatures provided the pressure is sufficient to maintain liquid phase.

The contact time in both extraction steps is ordinarily short, being on the order of ten minutes; however, some stocks may require a longer period of contact for successful extraction.

The ratio of acid to oil in the first extraction is preferably between about 0.05 and 0.3 volume of acid per volume of oil.

The ratio of hydrofluoric acid to oil in the second extraction step may vary from about 2 to 20 mols of acid per gram-atom of extractable sulfur contained in the raffinate of the first extraction step but it is preferred to use a ratio of 14-16 moles of HF per gram-atom of extractable sulfur contained in the raffinate of the first extraction step.

Both extraction steps may be conducted in either batchwise or continuous operation, and the conventional apparatus of the solvent extraction art may be readily adapted for use in the process of the invention. One of the methods of conducting this two-step extraction process, when using hydrofluoric acid in both steps, is to use the acid phase from the second extraction step, after it has been suitably purified and diluted, as the solvent-extractive phase for the first extraction step; then purifying and concentrating the acid from this latter step to a sufficient strength and purity so that it can be recycled and used as the acid for the second step, thereby eliminating the necessity of two acid concentration units. Such utilization of hydrofluoric acid in both extraction steps permits more efficient use of the acid solvent and simplifies solvent recovery and purification. Accordingly, the modification of the process of the invention is preferred over modifications employing different acids in the two extraction steps.

The second extract from either continuous or batch-type operation may be further treated to separate the sulfur compounds individually or according to chemical type.

Of the appended drawings, Figure 1 is a graphical representation of the variations of the character of the extract obtained from a high-sulfur gas oil with quantity of acid employed in the extraction step. Figure 2 is a graphical representation of the variation in the properties of the extract with the concentration of the acid employed.

Referring now to Figure 1, the data upon which the graph is based was gathered in a series of experiments to which a Santa Maria gas oil having a sulfur content of 2.46 per cent was extracted with varying quantities of 99.4 per cent hydrofluoric acid. The acid quantity is expressed in mols of acid per gram-atom of sulfur in the oil being extracted. It is seen that the extract yield rises sharply as the quantity of acid employed is increased, this sharp rise continues until a ratio of 14-16 mols of acid per gram-atom of sulfur is reached. The employment of higher acid to sulfur ratios produces only a slight increase in the yield of extract. The weight per cent of sulfur in the extract similarly shows a sharp rise as the ratio of acid to sulfur is increased from 0 to 8 mols of acid per gram-atom of extractable sulfur. The rise continues less sharply until a ratio of about 14 mols of acid per gram-atom of sulfur is reached after which further increases in the acid ratio produce little gain in the sulfur content of the extract. It is found that most efficient use of the acid in the extraction of sulfur compounds is obtained by employing 14-16 mols of acid per gram-atom of extractable sulfur in the extraction.

In Figure 2 of the appended drawings, data accumulated in a series of extractions of Santa Maria gas oil containing 2.46 per cent sulfur is summarized. A ratio of 14.8 mols of acid to each gram-atom of sulfur in the oil was maintained in each extraction and the concentration of hydrofluoric acid was varied from 50 to 99.4 per cent by weight. It is seen from this figure that the extract yield increased slowly with acid concentration until a concentration of 75-80 per cent was reached and then the yield increased much more rapidly with further increases in concentration. The per cent of sulfur in the extracted material also increased slowly with acid concentration until a concentration of about 80 per cent was reached and then rose abruptly to reach a maximum at about 86 per cent. As acid concentration was increased above 86 per cent and particularly as it was increased above 90 per cent, the percentage of sulfur in the extract declined. The extract obtained at acid concentrations from 50 to 80 per cent is small in volume and low in sulfur content indicating the presence in the oil of some non-sulfurous material, which is rather easily extractable. The decline in per cent sulfur content of the extract obtained at acid concentrations above about 90 per cent indicates the probability that some difficultly extractable non-sulfurous materials are removed by hydrofluoric acid at 90-100 per cent concentrations. Operation according to the process of the invention in its preferred modification employing hydrofluoric acid at about 80 per cent concentration in a first extraction step makes possible the removal of readily extractable non-sulfurous compounds in this step, then a second extraction step employing hydrofluoric acid at a concentration of 85-90 per cent makes possible the removal of an extract consisting essentially of sulfur compounds without the inclusion of the difficultly extractable non-sulfurous material which would be removed if acid at concentrations above 90 per cent were employed. While acid concentrations of 85-90 per cent are preferred in the second extraction step, the process may be conducted employing more concentrated or even substantially anhydrous hydrofluoric acid in the second extraction step in order to obtain the advantage of greater concurrent desulfurization of the oil in addition to the recovery of an extract consisting predominantly of sulfur compounds.

The process of the invention is illustrated by the following examples:

EXAMPLE I

Santa Maria oil was extracted according to the process of the invention employing perchloric acid of 70-72 per cent concentration in the first extraction step and hydrofluoric acid of 85.7 per cent concentration in the second extraction step. Properties of this gas oil are shown in the following Table I. The gas oil and perchloric acid were shaken in a laboratory separatory funnel for 5-10 minutes. After standing, the extract layer was separated. The raffinate was washed with water, then with caustic, and then with water again. After washing, the raffinate was filtered and inspected. Following inspection, the raffinate was extracted with 85.7 per cent hydrofluoric acid in a manner similar to that of the first extraction step. The raffinate and extract of the second extraction were washed and inspected. Data from this experiment are summarized in the following Table I.

Table I

	Extraction 1			Extraction 2

Per Cent Sulfur Compounds.....						

Note: ¹ Yield from Density (Wt. per cent) is calculated in the following manner:

$$\text{Yield from Density (wt. per cent)} = \frac{(D_e - D_r)}{(D_e - D_r) D_e}$$

where:

D_e =density of charge.

D_r =density of raffinate.

D_e =density of extract.

² Molecular weights were determined from observations of the freezing point lowering of benzene in benzene solutions of the materials whose molecular weight is being determined. The method is set forth in "Physical Methods of Organic Chemistry," by Weissberger, Interscience Press, 1945, at page 35 et seq.

It is seen from Table I that an extract containing 31.3 per cent sulfur compounds was obtained in the second extraction step and that a substantial degree of desulfurization of the gas oil was concurrently obtained.

EXAMPLE II

A quantity of Santa Maria gas oil was subjected to a two-stage acid extraction employing hydrofluoric acid as the extractive solvent in both stages, the acid concentration was 80.4 per cent in the first stage and 85.9 per cent in the second stage. The results of the extractions are summarized in the following Table II:

Table II

¹ See Remarks following Table I.

It is seen from Examples I and II that hydrofluoric acid of 80 per cent concentration and

perchloric acid of 70 per cent concentration are approximately equivalent in the first extraction step of the process of this invention and it has similarly been found that sulfuric acid of about 82 per cent concentration is approximately equivalent to hydrofluoric and perchloric acids at their respective preferred concentrations in the first extraction step.

It is not intended that this invention be limited to the examples given for the sake of illustration but rather to extend it to such modifications within the skill of the art as are within the scope of the appended claims.

I claim:

1. The method of separating a concentrate of organic sulfur compounds from sulfur-contain-

ing petroleum oils which comprises first extracting said oil with a mineral acid having a concentration not exceeding 80 per cent by weight and thereafter extracting the raffinate of the first extraction with hydrofluoric acid having a concentration of at least 85 per cent by weight.

2. The method of separating a concentrate of organic sulfur compounds from petroleum oils of medium to high sulfur content which comprises first extracting the oil with a strong mineral acid at a concentration not exceeding about 80 per cent by weight to remove readily extractable non-sulfur compounds from the oil and thereafter extracting the raffinate of the first extraction step with hydrofluoric acid at a concentration of at least 85 per cent by weight to separate an extract consisting predominantly of organic sulfur compounds.

3. The method of separating a concentrate of organic sulfur compounds from petroleum oils of medium to high sulfur content which comprises first extracting one volume of oil with 0.05 to 0.3 volumes of a strong mineral acid at a concentration of 50 per cent to 80 per cent by weight to remove readily extractable non-sulfur compounds from the oil and thereafter extracting the raffinate of the first extraction with hydrofluoric acid at a concentration of at least 85 per cent by weight to separate an extract consisting predominantly of organic sulfur compounds.

4. The method of separating a concentrate of organic sulfur compounds from petroleum oils of medium to high sulfur content which comprises first extracting one volume of oil with 0.05 to 0.3 volumes of a strong mineral acid at a concentration of about 50 to 80 per cent by weight to remove readily extractable non-sulfur compounds from the oil, thereafter extracting the raffinate of the first extraction with hydrofluoric acid at a concentration of at least 85 per cent by weight to separate an extract consisting predominantly of organic sulfur compounds and employing in the second extraction step 14-16 mols

of hydrofluoric acid per gram-atom of extractable sulfur contained in the raffinate of the first extraction step.

5. The method of separating a concentrate of organic sulfur compounds from petroleum oils of medium to high sulfur content which comprises first extracting one volume of oil with 0.05 to 0.3 volumes of hydrofluoric acid having a concentration of about 80 per cent to remove readily extractable non-sulfur compounds from the oil, thereafter extracting the raffinate of the first extraction step with hydrofluoric acid having a concentration of about 85-90 per cent and employing in the second extraction 14-16 mols of hydrofluoric acid per gram-atom of extractable sulfur contained in the raffinate of the first extraction step.

6. The method as defined in claim 5 wherein the acid employed in the first extraction step is perchloric acid at a concentration of about 70 per cent.

7. The method as defined in claim 5 wherein the acid employed in the first extraction step is sulfuric acid at a concentration of about 80 per cent.

8. The method as defined in claim 5 wherein the petroleum oil is a Santa Maria gas oil.
